UNITED STATES PATENT OFFICE.

FRANCISCO CAVALLARO, OF SAN JOSÉ, CALIFORNIA, ASSIGNOR OF ONE-THIRD TO IGNAZIO TRAPANI, OF SAN FRANCISCO, CALIFORNIA.

ATTACHMENT FOR ARTESIAN WELLS.

SPECIFICATION forming part of Letters Patent No. 627,251, dated June 20, 1899.

Application filed February 20, 1899. Serial No. 706,134. (No model.)

To all whom it may concern:

Be it known that I, FRANCISCO CAVALLARO, a citizen of the United States, residing at San José, county of Santa Clara, State of California, have invented an Improvement in Attachments for Artesian Wells; and I hereby declare the following to be a full, clear, and exact description of the same.

My invention relates to improvements in Artesian wells.

It consists, essentially, in the combination, with the well and its casing, of an annular chamber adapted to fit within the casing, with gasket and expanding device for making a tight joint between the two, and concentric pipes fixed to and extending downwardly from the chamber within the well-casing and forming an air-chamber exterior to the suction-pipe, one or more pipes through which air 20 may be forced under pressure into said chamber, whereby the body of water within the well may be forced upwardly to the surface.

It also comprises details of construction which will be more fully explained by reference to the accompanying drawings, in which—

Figure 1 is a vertical section on line xx of Fig. 3. Fig. 2 is a top view of the guide-nut. Fig. 3 is a horizontal section on line yy of Fig. 1.

A is the well-casing.

B is a suction-pipe extending down to any suitable point within the well. Fixed upon the bottom of this pipe is a flanged disk or open-bottomed chamber C, having an expandable rubber gasket D, of approximately the same diameter, fixed upon the top and having an upwardly-diverging interior which is adapted to receive an expanding device E. 40 This is in the form of a cone adapted to enter the gasket D and press its sides outwardly, so as to make a tight fit between it and the sides of the well-casing.

In the present case I have shown a novel 45 means for operating the expander E. A tube F, of slightly-larger diameter than the suction-pipe B, surrounds it and has screw-threads cut upon the lower end, which fit into the top of the expander E, as shown at e. 50 Through this horizontal top and interior to

the sides of E extend bolts G, of sufficient length to pass through the expander and the gasket D and screw into the casting C, so that they form guides upon which the head of the expander is slideable as it is raised or depressed. Upon the upper end of the tube F is a nut H, loosely turnable upon a flange or other guide at the top of the pipe F. The interior of this nut is turnable upon a screw-threaded exterior portion of the suction-pipe 60 B, and when it is thus turned it will advance the tube F and the expander E in either direction, the expander being prevented from turning by the guide-pins G, as shown.

B' is a continuation of the suction-pipe B, 65 and it extends to a point from near the bottom of the well. Threaded to the interior of the outer flange of the casting C is another pipe I, concentric with the pipe B' and with the casing A, and this pipe I extends down 70 and terminates at a point a greater distance above the bottom of the well than the pipe B'. The space between the pipes B' and I forms a chamber into which air is introduced through an air-pipe J, extending from the surface and 75 passing through the casting C, so that air under any desired pressure may be delivered into the chamber between the pipes B' and I. As the water within the well normally rises up to a considerable distance within the pipe 80 B' and between it and the pipe I, the pressure of the air upon the surface of the water between the two pipes acts to force the water upward within the pipe B' and I, and this pressure may be of any desired degree, so as to 85 either force the water entirely out of the well, or by maintaining a certain pressure the water which flows into the well will be caused to rise to a much higher point continuously than it would under normal conditions, so 90 that it will be within easy reach of the pump. By closing the air-pipe and applying a strong suction through the suction-pipe an increased flow of water into the well is effected.

Having thus described my invention, what 95 I claim as new, and desire to secure by Letters Patent, is—

1. The combination with the casing and the suction-tube thereof, of an annular casting surrounding the lower suction-tube and form- 100

ing an air-chamber, an expansible gasket fixed to the upper surface of the casting, an expander adapted to enter and expand said gasket, vertical guide-pins fixed in said casting and passing loosely through the expander, a tube surrounding the suction-pipe and connected with the expander, and a follower swiveled upon the upper portion of the tube and threaded upon the suction-pipe whereby the expander and connected parts are raised and lowered.

2. The combination with the casing and the suction-tube, of an annular open-bottom casting loosely fitting the casing and disposed around the lower portion of the tube, an expansible gasket fixed to the upper portion of the casting, a conical expander adapted to engage the interior of the gasket, vertical guide-pins fixed in said casting and passing loosely through the expander, a tube surrounding the suction-pipe and having its lower end secured to the expander, a central exten-

sion B' of the lower end of the suction-tube, extending to a point near the bottom of the well and a single tubular extension I connected with the inner wall of the casting and extending downward to a less distance intermediate between the casing and the extension of the suction-pipe and forming an air-chamber between itself and said extension B', an air-pipe passing through the expander and gasket and entering said air-chamber, and a nut and collar turnable upon the upper portion of the tube which carries the expander said collar engaging threads upon the outside of the suction-tube whereby the expander is raised and lowered.

In witness whereof I have hereunto set my hand.

FRANCISCO CAVALLARO.
